DELAYED ACTION MAGNETIC CIRCUIT BREAKER

Filed Dec. 7, 1950

UNITED STATES PATENT OFFICE

2,690,528

DELAYED ACTION MAGNETIC CIRCUIT BREAKER

Kurt W. Wilckens, Morrisville, Pa., assignor to
 Heinemann Electric Company, Trenton, N. J.,
 a corporation of New Jersey

Application December 7, 1950, Serial No. 199,597

8 Claims. (Cl. 317—178)

1

My invention is an improved circuit breaker of the type in which a switch blade has operatively associated therewith an electromagnetic trip mechanism having an armature attracted, on overload, by an electro-magnet, and the leading object of my invention is to increase the effectiveness of the electro-magnet.

In accordance with my invention, the electro-magnet comprises a solenoid coil and magnetically permeable members in the magnetic field of the coil and normally separated from one another by a gap or gaps, one or more of which are automatically closed on overload to produce an electro-magnet having adjacent poles of opposite polarity for attracting the armature of the trip mechanism. On a given current flow through the coil, the attraction of the armature, when the gaps are so closed that the members form a closed U-magnet, is approximately eleven times the attraction that is exerted when the gaps are open, thereby insuring adequate power to insure the operation of a tripping mechanism upon the occurrence of an overload or permitting a decrease in the number of ampere turns in the coil.

The gap closer preferably consists of a piston-like plunger or core having a flanged head and enclosed in a tube or dash pot of non-magnetizable material, within the electro-magnetic coil, so that the movements of the core in response to the pull of the magnetic field are retarded to a desired degree before making contact with the permeable members.

The principles of my invention and the best mode in which I have contemplated putting such principles into practice will further appear from the following description and the accompanying drawings in illustration thereof.

In the drawings, Fig. 1 is a part sectional side elevation of a circuit breaker embodying my invention; Fig. 2 is a detached longitudinal sectional view of the electro-magnetic mechanism with the gaps closed; Fig. 3 is a transverse sectional view taken on the line 3—3 of Fig. 2; Fig. 4 is a transverse sectional view taken on the line 4—4 of Fig. 2; Fig. 5 is a detached, fragmentary, sectional view showing a modification of the electro-magnetic mechanism; and Fig. 6 is a detached, fragmentary sectional view showing a further modification of the electro-magnetic mechanism.

As illustrated in the drawings, my invention is embodied in a circuit breaker comprising a magnetically permeable L-shaped frame having a leg 1 secured by a bolt 2 to the insulating base 3

2

A non-magnetic tube 5 is seated in and bushes an aperture 6 in the leg 1 and forms a dash-pot chamber 7 on one side of the leg. The chamber 7 communicates through an aperture 6 in the leg with a chamber 9 formed on the other side of the leg by a non-magnetic tubular cap 10 soldered to the leg coaxially with the tube 5 and spaced radially from the periphery of the aperture 6 so as to leave a surface 13 of the leg 1 exposed within the cap.

As shown in Figs. 1 to 5, the outer end of the tube 5 is sealed by pole piece 11 having a surface 12 exposed within the chamber 7.

A magnetically permeable, soft iron plunger 14 is housed in the chambers 7 and 9 and has a flanged head 15 movable into direct contact with the exposed surface 13. It will be noted that the tube 5 forms a non-magnetic spacer or bushing between the plunger 14 and the wall of the aperture 6 so as to minimize any drag on the plunger while moving through the frame leg 1, and that contact between the plunger 14 and frame leg 1 occurs only when the head 15 contacts the exposed face 13 of the frame between the edge of the aperture 6 and the tube 10 spaced radially therefrom.

The core 14 has a reduced nose 14a which as shown in Figs. 1 to 4, is movable into direct contact with the surface 12 to establish a metallic flux path between the frame leg 1 and the pole piece 11. The nose and head are normally biased away from the respective surfaces 12 and 13 by a coiled spring 16 interposed between the pole piece 11 and plunger 14 and encircling the nose 14a.

The inner surface of the cap 10 is provided with ribs or serrations 17 to preclude any tendency of the head 15 to adhere thereto by suction.

A solenoid coil 18 is wound on the tube 5 between the washers 19 and 20 respectively abutting the leg 1 and the pole piece 11 and has one end connected by a lead 21 with a load terminal (not shown) and its other end connected by a pig tail 22 with a movable switch blade 23 pivotally mounted on the ears 24 of the frame. The frame has a magnetically permeable leg 1' formed integrally with the leg 1 and extending transversely thereto along the solenoid coil 18 so that its forward end 26 forms a pole piece complementary to the pole piece 11.

An armature 27, adapted to bridge the pole pieces 11 and 26, is pivotally mounted on the ears 28 of the frame and has a curved finger 29 extending along the leg 1' and rockable by the movement of the armature 27 into engagement with a latch member 30 for unlatching the toggle formed by the links 31 and 32 connecting

the switch blade 23 with an operating handle 34 mounted on the ears 28, as more fully set forth in my Letters Patent No. 2,360,922.

When the toggle links are latched rigidly together, the rocking of the handle 34 moves the switch blade 23 into engagement with a fixed contact 35 connected with the line terminal 36. The blade 23 is normally biased away from the contact 35 by a spring 37 whenever the toggle links are unlatched by the rocking of the member 30 or whenever the handle 34 is turned on its pivot to the "off" position.

When the switch blade 23 is in engagement with the contact 35, current flows from the line terminal 36 through the contact 35, blade 23, pig tail 22, solenoid coil 18 and the lead 21 to the load terminal. The nose 14a is at all times within the magnetic field of the solenoid coil 18, but so long as the current does not exceed a predetermined overload, say 125% of rated capacity, the coiled spring 16 exerts a force sufficient to overcome the pull of the magnetic flux on the core 14 and keep the head 15 retracted against the ridges 17 (Fig. 1).

When, however, an overload in excess of the predetermined minimum flows through the solenoid coil 18, its magnetic flux causes the core 14 to move toward the pole piece 11 against the action of the spring 16 and against the retarding action of liquid or air 37 in the chambers 7 and 9. The time lag imposed by the dash-pot action will vary proportionately to the degree of overload. When the overload is at a minimum above the predetermined permissible amount, the core 14 will continue to move forward until its nose 14a contacts the pole piece 11 and the head 15 simultaneously contacts the leg 1, thereby eliminating the usual gap between the plunger and the frame caused by the non-magnetic tube wall and forming a closed metallic magnetic path from the pole piece 11 to the end 26 of the leg 1', thereby creating a strong magnetic attraction for the armature 27.

If the overload is substantially in excess of the predetermined permissible overload, a greater flux will be generated which will cross the diminishing gap between the plunger nose 14a and the exposed surface 12 and will cross the gap formed by the tube 5 between the plunger 14 and leg 1, and cause the pole pieces 11 and 26 to attract the armature 27 before the gaps are completely closed.

If there should be a short circuit, the magnetic flux generated by the coil 18 will be sufficient to instantly rock the armature 27.

The movement of the armature 27 toward the pole piece 11 lifts the finger 29 which rocks the latch member 30 and unlatches the toggle formed by the links 31, 32, thereby permitting the spring 37 to move the blade 23 away from the contact 35.

When a flux density lower than that resulting from the double contact of the plunger 14, as shown in Figs. 1 to 4, will satisfactorily operate the armature 27, the structure may be modified as shown in Figs. 5 and 6.

As shown in Fig. 5, the nose of the plunger 14 may be so shortened as to leave a slight gap between its tip and the surface 12 of the pole piece 11 and thereby avoid hammering on or displacement of the pole piece. The gap produces a certain reluctance into the magnetic circuit, but the contact of the head 15 with the frame section 13 will result in a flux density at the pole pieces 11 and 12 substantially as great as though the core contacted the pole piece surface 12 and was

separated throughout from the frame 1 by the tube 5.

As shown in Fig. 6, the tube 5 may have an integral end and body of non-magnetizable material, as brass. When the head 15 contacts the frame surface 13, the tip of the plunger nose will be adjacent to or in contact with the end of the tube and flux will flow from the tip of the core through the tube end, across the air gap, through the armature, and across the air gap to the pole 26, thereby attracting the armature.

Having described my invention, I claim:

1. In a device of the character described, the combination of an armature and an electromagnet in operative association with said armature and including a coil, an apertured, magnetizable frame in the magnetic field of said coil, a sealed retarding dash-pot having tubular walls of non-magnetizable material projecting oppositely from said frame and surrounding the aperture therein, said frame having a section adjacent to said aperture exposed within said dash-pot, and a core movable longitudinally in said dash-pot and having a magnetically permeable member movable into contact with said exposed section to close a gap in a magnetic circuit and abnormally increase the flux attracting said armature.

2. In a device of the character described, the combination of an armature and an electromagnet in operative association with said armature and including a coil, an apertured, magnetizable frame in the magnetic field of said coil, a sealed retarding dash-pot having tubular walls of non-magnetizable material projecting oppositely from said frame, one of said tubular walls forming a bushing in said frame aperture, said frame having an exposed section within said dash-pot, and a core movable longitudinally in said dash-pot and having a flange movable into contact with said exposed section of said frame.

3. In a device of the character described, the combination of a solenoid coil having a pole piece adjacent to one end thereof, a magnetically permeable member having a part extending along the exterior of said coil and forming a pole piece, said pole piece and member normally having multiple gaps between them, a magnetically permeable member within the magnetic field of said core and movable thereby into direct contact with both said pole piece and first named member to close a gap between them, a non-magnetic sleeve encircling said movable member throughout its length and an armature operatively associated with said pole pieces and attracted thereby and shortening a gap between them.

4. In a device of the character described, the combination of a magnetically permeable frame having transverse legs, non-magnetic walls forming chambers on opposite sides of one of said legs, a solenoid coil surrounding one of said chambers and extending along a leg of said frame, a pole piece at one end of said last named chamber, said frame and pole piece having surfaces exposed in said chambers, a magnetically permeable plunger sealed in said chambers movable in said chambers by magnetic flux of said coil toward said exposed surfaces of said pole piece and frame, and an armature in operative association with said pole piece and frame.

5. In a device of the character described, the combination of a solenoid coil, non-magnetic walls forming sealed communicating chambers within and without said coil, a pole piece at one end of said coil and having a wall exposed in

one of said chambers, a magnetically permeable member extending along the exterior of said coil and having a section forming a pole piece complementary to said pole piece first named and a section having a wall exposed in one of said chambers, and a magnetically permeable plunger having an enlarged portion and in said chambers and movable by the magnetic flux of said coil toward contact with both of said exposed surfaces.

6. In a device of the character described, a magnetically permeable frame having transverse legs, tubes forming sealed communicating chambers on opposite sides of one of said legs and communicating therethrough, a solenoid coil encircling one of said tubes, a pole piece at the end of said coil, and a magnetically permeable plunger in said chambers and having a nose movable toward said pole piece and a head movable into direct contact with said first named leg to close gaps in a magnetic circuit, a spring tending to bias said plunger nose and head away from said pole piece and leg respectively, and an armature movable toward said pole piece and frame by magnetic flux abnormally increased by closure of said gaps.

7. In a device of the character described, a magnetically permeable frame containing an aperture, a sealed retarding dash pot including a non-magnetic tube seated in said aperture and a tube secured to said frame and radially spaced from the edge of said aperture so as to leave a surface of said frame exposed within said last named tube, a magnetically permeable plunger in said tubes and having a flange movable into

contact with said exposed surface to close a gap in a magnetic circuit, and a solenoid coil encircling said first named tube.

8. In a device of the character described, the combination of a sealed dash pot having a magnetically permeable member forming a pole piece, an electromagnetic coil encircling said dash pot adjacent to said pole piece, a magnetically permeable frame in the field of said coil and having a member forming a pole piece complementary to but of opposite polarity from said first named pole piece, an armature in the field of said pole pieces and normally spaced therefrom but attracted thereby upon the flow of current through said coil, and a magnetically permeable core movable in and retarded by said dash pot and having an enlarged portion, said core being movable into magnetic contact with said first named pole piece and with said frame and said armature being movable into magnetic contact with said pole pieces upon the flow of abnormal current through said coil.
